ABSTRACT

An enhanced carburetor deicer composition consisting of benzoic acid and a freeze-point depressant or a surfactant deicer.

2 Claims, No Drawings

CARBURETOR ANTI-ICING COMPOSITION

This application is a continuation of copending application Ser. No. 533,246 filed Mar. 10, 1966, now abandoned.

This invention relates to a gasoline composition having improved anti-icing properties. More particularly, this invention relates to a gasoline composition having incorporated therein a synergistic mixture of a deicer and benzoic acid. The benzoic acid seems to impart a synergistic strength to the deicer so that it becomes most effective in preventing carburetor icing.

Carbureted internal combustion engines have a tendency to stall, at idling speeds or while the engine is still cold. Such stalling is caused by the formation of ice on the throttle plate and adjacent surfaces within the carburetor. The ice blocks the intake passage and literally "starves" the engine of gasoline. With the trend toward more volatile gasolines, which further aggravates the sudden chilling and consequent ice deposition of any moisture in the gasoline, or in the air passing through the carburetor, the problem becomes quite acute.

Attempts have been made to alleviate the problem by incorporating water-soluble freeze-point depressants, such as alcohols (methanol, ethanol, isopropanol, diacetone alcohol, and amino alcohol), glycols (ethylene glycol, butylene glycol, methyl pentanediol), glycol ethers (diethylene glycol monobutyl ether, ethylene glycol monoethyl ether), acetates (OXO bottoms), amides (dimethylformamide), carbonates (ethylene carbonate) and mixtures of the above, into the gasoline. But this approach requires relatively large amounts of depressant, in the range of 0.1 to 5 percent. Such large amounts make commercial use of the freeze-point type depressant uneconomical.

Another class of deicers is the surfactant-type deicer. These modify the cohesive ability of the ice so that it does not readily stick to the throttle plate and adjacent surfaces within the carburetor. U.S. Pat. No. 2,706,677 typifies this class. It discloses high-boiling amines as deicers. U.S. Pat. No. 2,891,850 also typifies this class. It discloses the use of N-alkyl substituted alkylene diamines as deicers. Another patent, U.S. Pat. No. 3,055,746 discloses the use of amine-monocarboxylic acid adducts as antistall, anti-icing agents.

While much has been done in this field of technology, there is still area for improvement. A low-cost, highly effective stable and compatible deicer compound or composition for gasoline is still needed.

Accordingly, an object of this invention is to provide a novel deicer composition.

Another object is to provide a more economical gasoline composition having deicer characteristics.

Still another object is to provide compositions of the above character which are relatively low in cost.

A further object is to provide compositions of the above character which are highly effective.

A still further object is to provide compositions of the above character which are stable.

Other objects of the invention will in part be obvious and will in part appear hereinafter.

A gasoline composition has now been found having improved anti-icing properties due to the incorporation of a synergistic mixture of a deicer and benzoic acid. More particularly, when benzoic acid is added to a deicer of either the surfactant type or of the freeze-point depressant type, the carburetor anti-icing properties are synergized. A small amount, 0.1 to 25 percent by weight of the deicer of benzoic acid is sufficient to accomplish the synergism. Preferably, a determination should be made as to the effective quantity for the particular deicer utilized. It might be noted that amounts in excess of the optimum effective quantity with increasing concentration tend to reverse the deicer effect.

The invention accordingly comprises a composition of matter possessing the characteristics, properties, and the relation of components which will be exemplified in the composition hereinafter described, and the relation of one or more of such steps with respect to each of the others thereof, and the scope of the invention will be indicated in the claims.

For a fuller understanding of the nature and objects of the invention, reference is now made to specific examples:

EXAMPLE I

The named deicer with or without benzoic acid, in the amounts indicated in Table I, are added to a commercial, full boiling range, winter grade gasoline with no additives therein. (Reid Vapor pressure = 13.5 p.s.i.; ASTM 50 percent boiling point = 180° F.).

The test conditions of the deicer test are 42° F. and 85 percent relative humidity. Each test is run for 6 minutes. The results of each test are obtained by readings taken from a manometer every 30 seconds. At the conclusion of each 30-second interval, temperature, vacuum and gasoline consumption are recorded. The chemical additive having the lowest vacuum reading at the end of 6 minutes exhibits the least amount of ice adherence or formation on the throttle plate and throttle area of the carburetor and is rated the best potential deicer. All tests recorded are started with a manifold vacuum of 4 inches.

It might be noted from Table 1 above that some of the deicers tested appear to be good carburetor anti-icers by themselves, while others exhibit little or no effect. When small amounts of benzoic acid are added, there is an improvement in the anti-icing property. This synergism occurs whether the benzoic acid is added directly to the gasoline or premixed with the deicer and then the mixed deicer-benzoic acid added to the gasoline.

The objectives of this invention may be accomplished by utilizing 0.1 to 25 percent by weight based on the deicer of benzoic acid and preferably the optimum effective quantity needed to accomplish the greatest synergism and the least reversal of the deicer effect.

It might be noted that the salt of benzoic acid is not the agent that accomplishes the deicer result. Indeed, if a stoichiometric amount of the acid and the deicer were used, a reversal of the deicer effect may occur. This is illustrated in Table 1 above—compare tests 10 and 11, 14 and 16, 26 and 28. There is an optimum concentration within the above ranges for each deicer. As the concentration of benzoic acid is then increased, the reversion effect begins and becomes more aggravated. It is therefore evident that the salt of benzoic acid is not the true deicer agent. Apparently it is the combined effect of the benzoic acid as well as any salt that may be formed.

Any deicer of the surfactant or freeze-point depressant type may be used. Many are disclosed in the introductory portion of this application. It is preferred, for economical reasons, to employ the cationic surfactant type and particularly the amines. Typical amines that are useful are the fatty mono- and diamines wherein the fatty chain has from eight to 22 carbon atoms. Typical amines are: caprylylamine, laurylamine, myristylamine, palmitylamine, stearylamine, arachidylamine, behenylamine, and N-capryl 1,3 propane diamine, N-lauryl 1,3 propane diamine, N-myristyl 1,3 propane diamine, N-palmityl 1,3 propane diamine, N-stearyl 1,3 propane diamine, N-arachidyl 1,3 propane diamine, and N-behenyl 1,3 propane diamine, or mixtures thereof.

The deicer-benzoic acid mixture accomplishes the deicer effect when used in gasoline. Usually, 10 to 300 milligrams of surfactant-type deicer and 100 to 1,000 milligrams of freeze-point depressant-type deicer per liter of gasoline is sufficient, and the preferred amount is 100 and 500 milligrams of surfactant-type and freeze-point depressant-type deicer, respectively, per liter of gasoline.

It will thus be seen that the objects set forth above, among those made apparent from the preceding description, are efficiently attained, and, since certain changes may be made in the above composition of matter and the process without departing from the scope of the invention, it is intended that all matter contained in the above description shall be interpreted as illustrative and not in a limiting sense.

It is also to be understood that the following claims are intended to cover all of the generic and specific features of the invention herein described, and all statements of the scope of the invention, which, as a matter of language, might be said to fall therebetween.

Now that the invention has been described, what is claimed is:

1. A gasoline composition having improved deicing properties comprising (1) gasoline, (2) as a deicer an amine selected from the group consisting of alkyl monoamine and alkyl diamine wherein the alkyl group has from eight to 22 carbon atoms and (3) 0.1 to 25 percent by weight of benzoic acid to synergize the deicer effect.

2. A gasoline composition having improved deicing properties comprising (1) gasoline, (2) an N-sec-C₁₁-15alkyl-1,3 propane diamine as deicer and (3) 0.1 to 25 percent by weight of benzoic acid to synergize the deicer effect.
